ELECTRIC CONTROL

Ira E. McCabe, Chicago, Ill.

Original application April 18, 1935, Serial No. 17,073, now Patent No. 2,075,951, dated April 6, 1937. Divided and this application January 2, 1937, Serial No. 118,720

4 Claims. (Cl. 200—122)

This invention relates to improvement in electric controls and to a simplified device for such controls wherein it is desired to open the circuit after a predetermined time in case of failure of certain functions of other devices in the control or controlled circuit, and more particularly to that type of device used to stop the equipment upon failure of combustion or ignition in fluid fuel burners.

10 In a number of previous applications, this applicant has disclosed various methods and means of producing such devices, many of which have attained considerable commercial use. One form disclosed in Patents Nos. 1,686,286 of October 2, 15 1928, and 1,690,689 of November 6, 1928, comprised a normally open switch with detachable means for holding the switch in closed position releasable by heat, generated by an electric current, including means for varying the current passing through said heat generated means in accordance with temperature or pressure changes.

Another form disclosed in this applicant's Patent No. 1,681,421 of August 21, 1928, involved the use of a similar thermal safety device included in a circuit to a fluid fuel burner wherein the heat generated means for releasing the safety switch was constantly energized during the operation of the burner and means included, operable upon the establishment of combustion, to divert a stream of air from the burner draft tube, produced by the burner fan, to cool the heat generated means.

Still another form, and one which has been successfully applied to the extent of wide commercial use, is disclosed in this applicant's Patents Nos. 1,675,897 of July 3, 1928; 1,648,390 of November 8, 1927; 1,884,045 of October 25, 1932; 2,015,952 of October 1, 1935, and 2,024,697 of December 17, 1935, which incorporated the use of electrically operated thermally actuated safety releases in combination with switching means operating under certain conditions to establish a shunt circuit by which the current may be bypassed around the electrically operated thermal release.

Although the devices wherein the shunting circuit is employed are being commercially adapted in one form or another in electrical controls of the character herein disclosed, they have presented problems when attempts to apply them to certain classes of applications have been made, as well as leaving room for improvements in their more common applications.

55 When the heat generating means is in series

with the load, and the operating requirements of such loads as solenoids or magnetically operated devices is small, after starting, the impressed voltage on the load is increased when the shunt circuit is closed, and the load is thus subjected to additional current. A reverse of this characteristic would be more suitable or desirable as an increase in resistance of the circuit would limit the current instead of it being increased as it is in the shunt circuit applications heretofore referred to. Furthermore, the heat generating means upon being shunted out naturally cools and in the event the shunt circuit is caused to open, as in the case of flame failure during the operation of a fluid fuel burner, the time required to effect the release of the safety switch necessitates the heating of the heat generating means which, however short as it is possible to make that period, may nevertheless be of such duration that should the flame extinguishment have 20 been caused by an air pocket or sludge of water in the fuel supply line, the burner, which continues to operate, would permit fuel to be admitted to a hot combustion chamber without immediate means to ignite it, thus producing a hazardous condition for a longer period of time, 25 than with the method herein disclosed.

The advantages of using mercury switches as circuit breakers are well known, but their use in electrical circuit controls, such as disclosed in 30 the aforementioned patents, particularly Nos. 1,675,897 and 1,884,045, require considerable mechanism for the development of the power and means to operate them, or specially designed shunting devices, as shown in Patent No. 1,648,- 35 390, so that in recent years there has been a trend toward producing controls of the disclosed character employing open contacts, even though they are inferior to mercury switches, being less durable and dependable and subject to pitting, 40 sticking and corrosion, solely through the necessity of meeting the demand in some quarters for cheaper controls, as they represent a major item in establishing the cost of oil burner installations.

It is, therefore, an object of this invention to 45 provide a simple device which may retain the use of a mercury switch as a circuit breaker, if desired, and of such construction as to dispense with the need of costly power producing mechanisms, and further, to eliminate the shunt circuit, and instead, to provide means whereby the 50 relationship between the releasable switch holding means and the electric thermal actuating means may be changed or one shielded from the other during normal running operation. By

this method, the heating element may be constantly energized during the operation of the controlled device, or mechanisms, and, if for any reason during that period should the elements comprising the safety mechanism be caused to assume their normal starting positions, a much shorter period of operation is thus attained in effecting the release of the safety switch than possible with the shunt circuit wherein only 5 a substantially constant tripping period is possible at any time upon, or during, a demand for operation of the controlled device, it being necessary to allow a sufficient tripping time to permit the burner to start normal operation when the 10 furnace is cold as the oil may be slow in reaching the combustion chamber due to the necessity of the pump having to bring it from a remotely located tank.

By means of this invention, it is possible to reduce to a minimum, which probably will not be exceeded, the number of contacts heretofore found necessary in controls of this character to make and break a circuit to meet the greater 15 number of applications. The simplicity of construction, which this feature affords, makes possible its use as a reliable control of great utility in fields where it is adaptable. This application is a division of this applicant's prior copending application Serial No. 17,073, filed April 18, 1935, 20 and which matured into Letter Patent No. 2,075,951, of April 6, 1937.

With these and other objects in view, reference is made to the accompanying drawings which illustrate preferred forms of this invention with 25 the understanding that detail changes may be made without departing from the scope thereof.

In the drawings:

Figure 1 is a fragmentary view partly in side elevation and partly in section of an embodiment 30 of this invention.

Figure 2 is a view in front elevation of Figure 1 illustrating the parts in their normal starting position.

Figure 3 is a detail top plan view of the front 35 carrying plate and the mechanism mounted thereon including the tripping means for the tube switch less the heating element.

Figure 4 is a view of the parts illustrated in Figure 2 showing the heating element in inoperative 40 position.

Figure 5 is a view similar to Figure 4 showing the position of the parts after the tube switch has been tripped by the heating element.

Figure 6 is a detail view in front elevation of 45 the actuator for the heating element.

Figure 7 is a schematic wiring diagram of the circuit controlled by the device illustrated in Figure 2.

The embodiment of this invention as illustrated 50 is adapted to control the operation of a motor such as is employed to operate the mechanism of a fluid fuel burner, and is responsive to combustion conditions of the furnace to which the fluid fuel burner is applied, to trip the safety switch by means of changing the relation of a heating element and the thermostatic member of an electrical control such as disclosed in this applicant's prior Patent No. 2,024,697, of December 7, 1935, and in so doing combines the motor 55 and safety switch in one three-terminal mercury tube switch. The switch mechanism is mounted upon the base plate 1 which may form the bottom of an enclosure, not shown. To the rear of the base plate 1 a tubular member 2 is secured which is adapted to enter and be attached to the

stack leading from the furnace to the chimney in the usual manner. The free end of the tubular member 2 mounts one end of a spiral or helix of bi-metallic or thermal metal 3 which is secured thereto by the screw 4. The free end of the coil or helix is secured to the outer end 5 of an operating shaft 6 arranged axially of the tubular member 2. The base plate 1 is provided with a circular opening 7 within and concentric to tubular member 2. A hollow cylindrical member 8 is 10 mounted to rotate freely within the aperture 7. The inner end of the shaft 6 mounts the member 8 and the actuator for the heat element, as shown in Figure 6, and imparts an oscillatory movement to the member 8 and the switch carrying plate 9 upon contraction or expansion of the coil or helix 3 in response to combustion conditions within the furnace.

The secondary coil 10 of the repulsion relay is 15 carried by means mounted upon a pivot stud 11 in the same manner as disclosed in said prior application and inasmuch as the mechanism co-operating between the operating means for the carrier plate 9 and the secondary coil 10 is the same as that shown in said prior Patent No. 2,024,697, it is not thought necessary to further describe these parts herein.

The arm 12 extending from one side of the coil 10 and which is pivoted on the pivot stud 11 is provided with a depending angular termination 13 to which is pivoted on a switch carrier plate 14 which mounts in the clips 15 a three-terminal mercury tube switch 16, shown in detail in Figure 5. This switch is held in its normal operating positions substantially parallel to the arm 12 of the carrying means for the coil 10 by providing an extension 17 to the carrier plate 14 with an angular, upwardly extending member 18 which mounts at its free end a catch pin 19 normally adapted to engage under the nose 20 of a latch 21 member 21 mounted to rotate about a pivot post 22 in conjunction with a tripping plate 23 mounted thereon. The post 22 is mounted between plates 26 and 26^a held in parallel spaced-apart position by posts 24 and 28 and secured to the front plate 27 by screws 28^a. The tripping plate 23 is provided with a slot 25 through which the post 24 passes to limit the movement of said tripping plate about its pivoted point.

A bi-metallic or thermal member 30 in the 50 form of a plate is secured at its lower end upon the tripping plate 23, as shown. A thermal member including a circular portion 31 and spaced-apart parallel portions 32 and 33 extending therefrom is mounted in the position shown in Figures 3 and 5 with its shorter end 33 clamped upon the plate 26. The free end of the portion 32 mounts a catch pin 35 adapted to be engaged when cold by the member 30 when the switch 16 is in the normal open or closed position and with the nose of the latch 21 in engagement with the catch pin 19. A guide rod 36 is mounted concentric with the axis of the curved portion 31 of the thermal member upon a bracket, as shown in Figure 2, secured to the rear side of the front plate 27. A heating element including a spool 40 wrapped with electrical resistance wire 41 is mounted to reciprocate upon said guide rod 36 to be received entirely within the circular member 31 of the thermal member and to be withdrawn entirely therefrom. The carrier plate 9 is provided with an extension 42 of the bracket 43 secured thereto which is adapted to pass under the flange 44 of the spool 40 so that when the carrier plate 9 is in the position shown in Figure 7

2, the heating element is received entirely within in the circular portion 31 of the thermal member, and in rotating from this position to the position shown in Figure 4, the extension 42 engaging the flange 44 of the heating member moves the heating member over the guide rod 36 to withdraw it entirely from the thermal member to the position shown in Figure 4.

When the parts are in the position shown in Figure 2, as is assumed when the burner mechanism is idle, the passage of an electric current through the resistance coil 41 of the heating member, which in this position is entirely received within the thermal member, will cause the free end of the portion 32 thereof to move outwardly and release the catch pin 35 from engagement with the member 30, whereupon the tripping plate 23 is released and the free end thereof will rotate downwardly until the end of the slot 25 engages the stud 24 and in so doing will cause the latch 21 to be released from engagement with the catch pin 19 whereupon the safety switch 16 is rotated about the pivot of the carrier plate 14 to assume a position shown in Figure 5 in which the circuit is open through all of its terminals. The latch 21 is caused to rotate about its pivot post 22 in conjunction with the tripping plate 23 by forming the end of the tripping plate 23 on the side of its pivot post most distant from the stud 24 with an angularly extending termination 45 and providing the latch 21 with an extension from its upper end integral therewith whereby when the tripping plate 23 has been rotated so that its member 30 will be engaged by the catch pin 35, the nose 20 will be adapted to engage the catch pin 19 and support it in the axis of the pivot stud 11.

The mercury tube switch 16 is provided with terminals 46 and 47 entering from opposite ends both of which will be submerged in the mercury 48 when the switch is held in the open position by the latch 21 and the movable coil 10 of the relay is in its lowermost position, as shown in Figure 2, the position assumed when the circuit, of the coil 10 is opened, as hereinafter described. When this coil is energized and is repelled from the stationary coil 49 of the relay, as hereinafter described, the switch will be tilted about the pivot 11 without disturbing the connection between terminals 46 and 47, as shown in Figure 7. An additional terminal 50 enters the same end of the switch tube as the terminal 47 and is separated therefrom so that when the switch 16 is in the position described when the secondary coil 10 is de-energized, the mercury 48 in the switch 16 will be out of contact with said terminal 50, but when the coil 10 has been repelled to tilt the mercury tube switch to the position shown in Figure 7, the circuit will be completed between the terminals 47 and 50 by the flow of the mercury 48 to that end of the switch to submerge terminal 50.

From the schematic wiring diagram shown in Figure 7, it will be seen that the lead L from the commercial line passes through binding post 51 and through terminals 47 and 46 when the switch is tilted to the position shown in Figure 2 with the coil 10 resting upon the coil 49 and from terminal 46 to binding post 52 and from thence through the windings of the primary coil 49 of the relay to the binding post 53 and from thence to lead L' back to the commercial line. The windings of the secondary coil 10 are placed in circuit by lead 54 through binding post 55 and lead 56 through the room thermostat R to bind-

ing post 57 and from thence by lead 58 through the resistance winding 41 of the heating element to binding post 59 and from there through lead 60 to the other end of the winding coil 10. When the room thermostat is open, the secondary circuit will be broken and the coil 10 will rest upon the coil 49. When the room thermostat closes the secondary circuit through coil 10 it will be repelled, as shown in Figures 4 and 7, thereby closing the circuit between terminals 47 and 50 10 so that the commercial current will then pass through binding post 61, motor M, binding post 62 and back through lead L' to the commercial line. When the room thermostat is first closed, the heating element is received entirely within the thermal member, as shown in Figure 2, and when the room thermostat closes the secondary circuit, the heat produced by the resistance coil 41 of the heating element will cause the latch pin 35 to disengage the member 30 whereupon the latch 21 will release the switch tube 16 to rotate to the open position, as shown in Figure 5, unless combustion occurs within a predetermined time which is sufficient to cause the thermal coil 3 responsive to combustive conditions to rotate 25 the carrier plate 9 to remove entirely the heating element 40 from the thermal member 31, as shown in Figure 4. Should at any time after combustion has been initiated and the secondary circuit closed through the room thermostat R, the combustion fail or cease from any cause whatsoever, the thermal 3 responsive to combustive conditions will cool and cause the carrier plate 9 to rotate in the opposite direction and move the heating element to be received entirely within 30 the thermal element, whereupon the free end of the portion 32 of the thermal member will move outwardly and release the tripping mechanism to allow the switch 16 to open all circuits therethrough causing a shutdown of the burner 40 mechanism until the switch 16 is reset.

Although the disclosure of this invention has been confined to the description of its application with devices used in connection with the control of fluid fuel burners, the extent of its use is by 45 no means limited to that field alone.

The disclosure of means whereby a normally closed releasable switch may be held closed or released under certain conditions need not depend solely upon the temperature responsive helical coil operated mechanisms, as shown, for actuating the heating element. Other means for moving the heating element or shielding it are suggested in the patents referred to in the introduction. 55

What I claim is:

1. In a circuit control, a switch, a relay for opening and closing the switch, releasable means normally maintaining the switch in operative relation to the relay, a thermally actuated tripping device for the switch adapted to release the switch to open independently of the relay, a freely movable heating element adapted to operate the tripping device when in operative relation thereto, in combination with a temperature responsive device including an operating shaft adapted to be rotated in opposite directions upon variations of temperature, a plate mounted thereon for movement therewith, said heating element mounted upon a guide normally directing the 65 freely movable heating element by gravity into operative relation with the tripping device, and means upon the said plate to engage and bodily move the heating element out of operative relationship upon rotation of the operating shaft in 70 75

one direction and allow the heating element to assume the said operative relationship upon movement in the opposite direction.

2. Means to control the operation of a switch, including electrically operated means to open and close said switch, and releasable means normally maintaining the switch in operative relation to the first means including a thermally actuated tripping device adapted to release said second means to open independently of said first means, a freely movable heating element adapted to operate said tripping device when in operative relation thereto, and a temperature responsive device independent of the heating element for bringing the zone of heat from the heating element into and out of operative relation to the tripping device.

3. Means to control the operation of a switch, including electrically operated means to open and close said switch, and releasable means normally maintaining the switch in operative relation to the first means including a thermally actuated tripping device adapted to release said second means to open independently of said first means, a freely movable heating element adapted to operate said tripping device when in operative

relation thereto, movable means to increase and decrease the transfer of heat from the heating element to the tripping device while the heating element is energized, and means responsive to temperature changes independent of the heating element to actuate said movable means.

4. In a circuit control, the combination of a first switch and a second switch, a transformer relay for actuating said switches, a circuit to be controlled including the first switch, a circuit for the relay including the second switch, releasable means normally maintaining the switches in operative relation to the relay whereby the first switch may be opened and closed while maintaining the second switch closed, a third switch for controlling the operation of the relay in the secondary circuit of the relay, a thermally actuated tripping device for the releasable means adapted to release said means to open the first and second switches independently of the relay, a freely movable heating element adapted to operate the tripping device when in operative relation thereto, and means to control the relative proximity of the heating element and tripping device.
